UNITED STATES PATENT OFFICE.

JAMES S. PATES, OF WASHINGTON, PENNSYLVANIA.

ROOF SUPPORT FOR UNDERGROUND CHAMBERS.

Application filed August 19, 1926. Serial No. 130,222.

My invention relates to improvements in supports for the roofs of underground chambers. It is intended primarily for use in such relatively temporary situations as are exemplified in coal mines, and is applicable there in supporting the roofs of entries and chambers. Its advantages are its adaptability to spaces of varying and of indetermined size, its security and adequacy, its ease of application, its cheapness, and, by no means least, to the fact that the use of the invention does not involve the narrowing of the effective width of the passageway or chamber by the provision of posts, standing on the floor of the chamber and commonly required in providing roof supports in coal mines, and does involve increased head room.

The invention is illustrated in the accompanying drawings. Fig. I is a view in vertical and transverse section, illustrating diagrammatically a mine entry having my invention applied to it; Fig. II is a view to larger scale and in side elevation of the component members of my roof-supporting structure; Fig. III is a view in side and end elevation of a bearing block preferably employed as a base or rest; and Fig. IV is a view in transverse section (in a plane which is radial with respect to the center of curvature) of the roof-supporting structure assembled. Figs. III and IV are to larger scale still than Fig. II.

I have developed my invention in its application in coal mines. These mines extend for long distances horizontally underground. In the working of the mines, passageways and rooms are opened, following the vein of coal. It is necessary, particularly in the entries, which have to be kept open during the working of remoter parts of the mine, and through which safe passage must be maintained for men and materials, to provide a well supported roof of timbers. Such a roof is required, to prevent the falling of loosened slabs of slate or other material, which otherwise liable to fall constitute a danger to life and to free and open passage. Hitherto, as already I have intimated, such timber roofs within mine spaces have ordinarily been carried on posts, and these posts resting on the floor of the passage and ranged along the walls, have diminished the effective width of the passageway by an amount equal to their thickness, or, rather, since a row of posts stands against either wall, by an amount equal to twice the

post thickness. Furthermore, posts are expensive, and in continued service have to be renewed, with incidental labor.

In Fig. I, C indicates a vein of coal, and S the strata of slate or other overlying deposits. E is the mine opening, and it will be understood that this may be an entry, passageway, room, or other space.

Instead of lining the opposite walls of opening E with posts, to carry transverse beams for the support of the roof timbers, I provide beams which at their ends may rest in recesses formed in the opposite walls and in the upper part of the chamber, to receive them. The beams of my invention are extensible and so variable and adjustable in length, and by virtue of this characteristic they may be accurately placed and supported as I have just indicated. Furthermore, the beams of my invention are arch-shaped, and by virtue of this shape they are more firmly secured at their ends and stronger to carry weight placed upon them, and afford increased head room. A beam of my invention is in Fig. I indicated at 1, and it carries the roof timbers 2. The beam extends transversely of the opening E and rests at its ends in recesses in the rock formed to receive it. The timbers 2 extend longitudinally immediately beneath the roof of the mine cavity where they take immediately the burden of any mass loosened from the overlying strata S.

Turning to Figs. II and IV it is to be remarked of the beam 1 that it is compound, and in this instance composed of three sections 11, 12, and 13. The ends of the sections overlap and are pinned together by pins which conveniently take the form of bolts 14. Pin-holes 15 are provided, groups of them at uniformly spaced intervals, and by such means the compound beam is adjustable in length and its component members may be secured to constitute a strong integral element of any particular length within the range provided and intended. Such step-by-step adjustability afforded by successions of equally spaced pin-holes is adequate to the service contemplated.

Strength is preferably given to the beam by forming it of channel iron, and in using channel iron the component sections are different in dimensions, to the end that one section may fit within another. Preferably the channel is placed with horizontally extending mid-web and downwardly extend-

ing flanges, and preferably the pin holes are formed in the flanges. All these features clearly appear in Fig. IV. A single pin 14 may extend across the channel and through aligned openings in the opposite pairs of overlapping flanges (as shown in Fig. IV), or, manifestly, shorter pins may unite each overlapping pair of flanges. In installation a plurality of pins in longitudinal succession preferably unites the overlapping ends of the sections.

The structure as a whole is arch-shaped, more effectively to sustain the burden, more firmly to rest upon its support, and affording increased head room.

The sill plates 3 are not essential; preferably, however, they are provided. They consist merely of short lengths of angle iron placed in recesses or notches in the wall 20 toward the upper part of the opening E formed to receive the ends of the beams 1 and to carry the structure. They serve to spread the thrust strains and to afford a firmer structure.

25 The greater the load upon the roof the firmer the anchorage of the ends of the beam. In particular locations it may be desirable

because of the crumbling nature of the deposits or for other reasons, more firmly to secure the ends of the beam, lest, even when bearing no considerable load, the crumbling away of the wall may cause loosening. It is entirely possible under conditions such as those suggested to make the anchorage more secure by driving a pin obliquely into the coal beneath the end of the beam, and in the position indicated at 6, Fig. I.

Manifestly my invention is applicable generally, in the support of the roofs of underground chambers.

I claim as my invention:

In a roof structure for an underground chamber a beam composed of a plurality of longitudinally adjustable upwardly arched channel-shaped sections nested one within another and pinned one to another through registered pin-holes, the said beam engaging at its ends opposite walls of the chamber, and load supporting members resting on the beam.

In testimony whereof I have hereunto set my hand.

JAMES S. PATES.
